UNITED STATES PATENT OFFICE.

JAMES E. OWEN, OF EDGELEY, NORTH DAKOTA.

WRENCH.

1,377,428.

Specification of Letters Patent. Patented May 10, 1921.

Application filed March 8, 1920. Serial No. 364,150.

To all whom it may concern:

Be it known that I, JAMES E. OWEN, a subject of the King of Norway, residing at Edgeley, in the county of Lamoure, State of North Dakota, have invented certain new and useful Improvements in Wrenches, of which the following is a description, reference being had to the accompanying drawing and to the figures of reference marked 10 thereon.

This invention relates to hand wrenches.

One of the objects of this invention is to provide a wrench with two jaws having free relative adjustment, said jaws also having 15 means for forcing them into gripping contact with the object in all positions of adjustment.

A further object of the invention is to provide a wrench including two jaws having 20 free relative movement into all positions of adjustment, said jaws also having coöperative means for forcing the same together to more firmly grip the work.

A further object of the invention is to 25 provide a wrench including two jaws having free relative movements into all positions of adjustment, together with interengaging means connected to said jaws for forcing the same together, at least one of 30 said means being adjustable whereby said means will interengage in all positions of adjustment of the jaws.

A further object of the invention is to 35 provide a wrench as above described in which the freely movable jaw is provided with means pivoted thereto and adapted to engage a portion of the stationary jaw for producing a gripping action between the jaws.

40 These and other objects will in part be obvious and will in part be hereinafter more fully disclosed.

In the accompanying drawings:—

Figure 1 represents a perspective view of 45 the wrench; and

Fig. 2 is a sectional view of the wrench showing the handle connected to the movable jaw disengaged from the shank portion of the fixed jaw.

50 In general, my improved wrench embraces a fixed jaw provided with a shank portion on which freely slides the movable jaw into various positions of adjustment. The movable jaw is provided with operating means

in the form of a handle pivoted thereto so 55 that it may be swung into contact with an extension of the shank, and such shank and handle have interengaging means adapted to force said jaws together to create a gripping action therebetween. In order to provide for this gripping action to take place in all positions of adjustment of the movable jaw, the connection between the latter and its handle is made adjustable.

Referring more particularly to the accompanying drawings, the wrench comprises a fixed jaw 1 provided with an integral shank 2 having an extension 3 in the form of a handle. At any suitable place therealong, this extension 3 is formed with a preferably integral upwardly extending lug or cam 4 hereinafter more specifically referred to. A movable jaw 5 is freely slidable on the shank portion 2 of the fixed jaw 1 and is freely adjustable therealong into all positions of adjustment to engage the object between these jaws. The jaws are provided with means for producing a firm gripping action on the object held therebetween in all positions of adjustment of the jaws, and to 80 this end there is provided a handle 6 having an extensible pivotal connection with the movable jaw 5. One form of connection is shown in the drawings in which the handle 6 is provided with a threaded bore 7 adapted to receive a threaded bolt 8 pivoted at 9 between two upstanding ears 10 integral with the jaw 5. In order to accomplish this inward forcing of the movable jaw toward the fixed jaw, the handles 6 and 70 extension 3 are provided with coöperating means which are adapted to engage as the handle is brought toward the extension 3 of the shank 2. One means for accomplishing 90 this comprises the before mentioned lug or cam 4 which is provided with an inclined face 11 preferably terminating in a face 12 perpendicular to the shank 3. It is of course obvious that the inclined face 11 may be continuous, or that these faces 11 and 12 100 may be in the form of a gradual curve, or in fact, any outline of cam surface may be used to produce the desired result. Coöperating with this cam face, the handle 6 is provided with a slot 13 having a correspondingly inclined inner face 14 adapted to engage the incline 11 on the cam 4. It is of course obvious that there are many other

105

ways of producing this inward forcing action of the freely movable jaw 5 with respect to the fixed jaw 1.

In operating the jaws as above described, 5 the handle is lifted into position as shown in Fig. 2 and the movable jaw 5 slid along the shank 2 until it makes contact with the object held therebetween. The handle 6 is now adjusted with respect to the bolt 8 so 10 that the inner face 14 of the cam slot 13 registers in its lowered position with the inclined face 11 of the cam 4. The handle 6 is now forced downwardly toward the extension 3 thereby permitting the cam 4 to 15 enter the slot and by the action of the cam faces forcing the jaw 5 into gripping contact with the object.

It is of course apparent that a device of this nature is very desirable, particularly 20 in cases where a wrench has to be used on an object of uniform size, inasmuch as the release of the handle never disturbs the adjustment of the jaws, so that the next time it is used, it is only necessary to slide the 25 movable jaw 5 into position and grip the handle and extension 3 together as in the ordinary use of a wrench.

It is obvious that minor changes in the details of construction may be made without departing from the spirit of the invention 30 as set forth in the appended claims.

Having thus described the invention, what I claim as new and desire to secure by Letters-Patent, is:—

1. A wrench comprising a stationary jaw 35 having a shank and an extension, a second jaw movable on said shank and provided with an adjustable extension pivotally connected solely to said second jaw and means on said extensions for producing a gripping action between said jaws while said extensions are forced together. 40

2. A wrench comprising relatively movable jaws, each having an extension, one of said extensions being pivotally connected to 45 one of said jaws and swingable bodily toward said other extension, means adapted to cause a gripping action between said jaws when said extensions are forced together, and means for producing an adjustment of 50 one of said extensions relatively to its jaw.

3. A wrench comprising a jaw having an extension, a second jaw slidable on said first jaw, a threaded member pivotally connected to said slidable jaw, a second extension adjustably threaded on said member, and cam means intermediate said extensions 55 adapted to produce a gripping action between said jaws when said extensions are forced together.

In testimony whereof, I affix my signature.
JAMES E. OWEN.
